US00D684737S

(12) **United States Design Patent**
Wolfe et al.

(10) **Patent No.:** **US D684,737 S**
(45) **Date of Patent:** **** Jun. 18, 2013**

(54) **EXTRACTOR HOUSING**

(75) Inventors: **Kevin A. Wolfe**, San Marcos, CA (US); **Richard A. Black**, Bellingham, WA (US); **William Bruders**, Sedro Woolley, WA (US); **Larry White**, Mount Vernon, WA (US)

(73) Assignee: **Dri-Eaz Products, Inc.**, Burlington, WA (US)

(**) Term: **14 Years**

(21) Appl. No.: **29/400,735**

(22) Filed: **Aug. 31, 2011**

(51) LOC (9) Cl. **15-05**

(52) U.S. Cl.

USPC **D32/21**

(58) **Field of Classification Search**

USPC D32/17-18, 21, 23-24, 31-34; 15/327.1-327.7, 320-321, 323, 353, 344, 15/329, 347, 246.2, 246.4, 301, 310, 313, 15/414, 328, 415.1-422.1; 210/167.16, 167.17; 285/7; 55/DIG. 3, 337, 345, 459.1, 429

(57) **CLAIM**

The ornamental design for an extractor housing, as shown and described.

DESCRIPTION

FIG. 1 is an isometric view of an extractor housing showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The features shown in broken lines depict environmental subject matter only and form no part of the claimed design.
